AUTOMOBILE IDENTIFICATION DEVICE

Filed Aug. 13, 1923

UNITED STATES PATENT OFFICE.

STRAUD K. WOOD, OF HUTCHINSON, KANSAS.

AUTOMOBILE IDENTIFICATION DEVICE.

Application filed August 13, 1923. Serial No. 657,013.

This invention relates to car identifying means and forms an improvement over my copending application for patent for car identifying means, filed July 7, 1923, Ser. No. 650,101, and the objects of the present invention are to provide means whereby an identifying card cannot be removed from position within the frame without mutilation, thus preventing the transference of a card from one car to another, and also to provide means for more firmly securing the card casing or frame to the automobile wind shield.

With the objects named in view, the invention consists in certain novel and useful features of construction and organization of parts as hereinafter described and claimed; and in order that it may be fully understood, reference is to be had to the accompanying drawing, in which:

Figure 1 is a face view of a portion of a wind-shield with a device embodying the invention in operative relation thereto.

Figure 2 is an enlarged perspective view of the device partly broken away.

Figure 3 is an enlarged section on the line III—III of Figure 1.

Figure 4 is an enlarged section on the line IV—IV of Figure 1.

Figure 5 is a face view of the invention as shown in Figure 4, but partly broken away.

Figure 6 is an enlarged section through an identifying card to show a modified form of mutilating knife.

Figure 7 is a section of the line VII—VII of Figure 6.

Figure 8 is a face view of an identifying card.

In the said drawing, where like reference characters identify corresponding parts in all of the figures, 1 illustrates a rectangular frame closed on its opposite faces by a pair of glass plates 2. The lower edge of the device is formed with a slot 3 for the reception of an identification card 4 between the plates 2, and said edge is also provided with a downwardly extending flange 5 adapted to be received between the packing and glass of a wind shield W, as described in my copending application, said flange being split transversely to provide ears 6 which may be bent upwardly to close the

slot 3 against the accidental dislodgment of the card.

In this improved construction, the front face of the frame 1 is formed, preferably in its upper corners, with enlargements 7 each having a slot or window 8 for the exhibition of the corners of the card, which are provided at said points with any suitable word or symbol, as "Transfer" as at 9, and vertically below said symbol the card is formed with an opening 10. Adapted to be received within the opening 10 and to catch the card and tear longitudinally when the card is removed through the slot 3, so that it will be impossible to remove a card without so mutilating it that such condition will be instantly noted through the opening 8 if an attempt is made to remove and substitute it in another frame, is a hook 11 formed on one end of a spring arm 12 which is riveted as at 13 to the inner face of the rear wall of the frame. (See Figures 4 and 5.)

It will be noted, in this connection, that the rearmost glass plate 2 is cut away as at 14 to accommodate the spring hook (see Figure 5). It will be evident that the hook 11 will permit a card to be inserted in position, as it will spring rearwardly to permit the card to be slid into position and that as soon as the opening 10 is in register, the hook will spring forwardly until stopped through abutment with the inner face of the front plate 2. When it is attempted to remove a card from position, the hook 11 engages the edge of the opening 10 and tears or irregularly mutilates the card longitudinally. If it is not desired to irregularly mutilate the card, a cutting hook 15 may be substituted for the hook 11, and the card will be formed with a rectangular opening 16 for the reception of the knife (see Figures 6 and 7). When a card of this character is removed from position, it will be apparent that its upper corners will be slit longitudinally by the cutting hook.

In order to secure the frame reliably in position to a wind shield, a suitable antirattle gasket 17 or the like is interposed between the back of the frame and the wind shield glass, and secured to the front sides of the frame are a pair of spring arms 18 bowed downwardly and formed with a connecting curved portion 19 of suitable contour to em-

brace the lower edge of the wind shield W. The portion 19 is tightly clamped against the windshield frame by means of bolts 20 engaged with the frame in any suitable manner, it being understood that the tendency of the spring arms 18 is to tightly clamp the frame against the face of the wind shield.

When it is desired to remove a card from position, the frame must be removed from the wind shield as the slot 3 is inaccessible when the device is in operative position.

From the above description, it will be apparent that I have produced a device of the character described which possesses all the features of advantage set forth as desirable; and while I have described and claimed the preferred embodiment of the same, I reserve the right to make all changes properly falling within the spirit and scope of the appended claims.

I claim:

1. The combination of a frame open at one of its faces, a glass plate fitting within and closing said open face of the frame, a card within the frame and fitting flatwise against the inside face of said glass plate and having an opening, and a mutilating element secured in said frame and engaged in said card opening, said element being adapted to mutilate a portion of the card upon the withdrawal of said card, the frame, card and mu-

tilating element being so arranged that the card cannot be removed from the frame without mutilation.

2. The combination of a frame open at one of its faces, a glass plate fitting within and closing said open face of the frame, a card within the frame and fitting flatwise against the inside face of said glass plate and having an opening, and a resilient mutilating element secured in said frame and adapted to yield to permit of the insertion of a card but upon the removal thereof to engage the card and mutilate same, the frame, card and mutilating element being so arranged that the card cannot be removed from the frame without mutilation.

3. The combination of a frame open at one of its faces, a glass plate fitting within and closing said open face of the frame, a card within the frame and fitting flatwise against the inside face of said glass plate and having an opening, and a resilient mutilating element secured in said frame and adapted to yield to permit of the insertion of a card and to be received within the opening thereof for the mutilation of the card upon its withdrawal.

In witness whereof I hereunto affix my signature.

STRAUD K. WOOD.
